REGISTER

Russell R. Dean, Los Angeles, Calif.

Application March 10, 1939, Serial No. 260,994

3 Claims.

(CL. 40—70)

This invention relates generally to registers, and contemplates more specifically devices incorporating in juxtaposition with a name register a plurality of numbered dials adapted for manual manipulation to record the number of articles designated by the name adjacent respective dials. An important adaptation of the present invention is embodied in a laundry register which may be employed by a householder who wishes to keep a record of the number and character of the pieces sent to the laundry and thereby facilitate verification of ownership and sufficiency of the returns. Such a device may be equally well adapted for use by the laundry to check the number of pieces received with those available for delivery. Numerous devices have been devised for analogous purposes which, by modification, might be employed in a somewhat similar manner to obviate the usual necessity of making a written list of articles to be laundered, but a common disadvantage of such conventional devices is the excessive cost of manufacture.

It is a general object of the present invention to provide a register, having a large number-capacity, comprising a board carrying a list of names of articles, and embodying windows in the board adjacent each name, with means associated therewith to bring appropriate numbers into visible registry with the windows.

More specifically, an object hereof is to provide in a device of the character above alluded to, an arrangement of parts, permitting utilization of cardboard or other inexpensive material for all principal pieces of the devices while combining maximum facility in use with minimum cost of manufacture.

Another object is to provide a board having a pair of windows formed therein, adjacent each of a plurality of names, in combination with a series of pins extending through openings in the board adjacent each window, respectively, each pin carrying a dial at the back of the board, whereby the pins afford both a means to rotatably mount the respective dials on the board, and means to individually rotate the dials.

Other objects and salient features of my invention will be apparent to those of skill in the art from an examination of the following description read in the light of the accompanying drawing, in which:

Fig. 1 is a front elevation of one embodiment of my invention adapted for use as a laundry register;

Fig. 2 is a sectional view taken on lines 2—2

of Fig. 1, depicting a preferred arrangement of the numbered dials;

Fig. 3 is a fragmentary elevation of the face of one of the decimal-digit-carrying dials.

Referring to the drawing in detail, the numerals of which indicate similar parts throughout the several views, 5 designates a face plate, which may be stamped from cardboard, of an embodiment of a register particularly adapted for use by a laundry for recording a list of the various articles of clothing and other textile pieces received. An area 6 at the top of the face plate 5 is illustrated as available for the name of the laundry or a division thereof, or other suitable notation.

Below the area 6, the names of all of the most common articles which the laundry is equipped to service are listed in spaced relation as hereinafter noted. It will be understood that the drawing is merely illustrative of the arrangement of the parts and in no way purports to represent a complete device, it being obvious that the names of numerous articles commonly serviced by a laundry are omitted from the embodiment depicted.

Below each name is a pair of windows 7 in the face plate 5 in which are moved numbers ranging from zero to one hundred, carried by means about to be described.

A back board 8 (Fig. 2), also preferably composed of cardboard and of a size equal to that of the face plate, is provided to reinforce the latter but is spaced therefrom by a spacer 9, comprising marginal strips 10 and a center strip 11. The face plate 5, back board 8, and intermediate spacer 9, are secured together by an adhesive or other suitable means in the arrangement illustrated, and when so assembled, openings 12 in the spacer between the marginal strips 10 and the center strip 11, register with the columns of double windows 7—7 at each side of the board, 40 respectively.

At each side of each double window 7—7, the face plate is provided with a hole which forms a bearing for a pin 13 mounted concentrically by suitable means to a dial 14 disposed between face plate 5 and back board 8 in the openings 12 formed in the spacer 9. Each dial 14 is of sufficient diameter to extend under its respectively-adjacent window 7, and is of a thickness substantially equal to that of the spacer whereby each dial will be frictionally held against rotative displacement between the face plate and back board. Pins 13 thus provide a means for rotatably mounting the dials 14 to which they 55

are secured, respectively, as well as a means for individually rotating the dials.

Each dial 14 carries the numbers from zero to nine on, respectively, lines coinciding with the axis of the dial adjacent the periphery thereof, i. e., a distance from the center of the dial substantially equal to the distance between the window under which the dial is located and the center of the dial. It will be observed that the numerals of each pair of dials are arranged consecutively to extend around the dial in counter-clockwise direction; the left-hand or decimal-digit recording dial of each double window has the numbers thereon disposed in upright position at the right side of the dial, while the numbers in the right-hand dial of each pair thereof are preferably arranged in a relatively-inverted position. It is desirable that the numerals from one to nine, inclusive, on each dial should be printed in a color readily distinguishable from the color of the zero as, for example, in red, with the zero shown in black, in order to differentiate the indicia showing in the windows below the names of articles of which a record is made 25 from those in which no articles are registered.

While I have described but one embodiment of my invention, it will be understood that numerous changes in size, design, number and proportion of the various parts may be made without departing from the spirit of my invention as defined by the appended claims.

What I claim and desire to secure by Letters Patent is:

1. In a device of the character described, a

face plate having a window therein, a bearing in said plate adjacent said window, a pin journalled in said bearing and extending to opposite sides of said plate, a dial relatively fixed to one end of said pin, a back board connected to said face plate bearing against said dial to retard rotation of the latter.

2. In a device of the character described, a face plate having a window therein, a bearing in said plate adjacent said window, a spacer having an opening therein secured to said face plate, a back board secured to said spacer, a pin journalled in said bearing and extending into the opening in said spacer, a dial relatively fixed to one end of said pin, said back board bearing against said dial to retard rotation of the latter.

3. In a device of the character described, a face plate having a pair of windows therein, said windows being adjacent one another and in horizontal alignment, a pair of pins extending rotatably through said face plate adjacent said windows, respectively, a dial relatively fixed to each of said pins, said dials having annuli thereof in partial registry with said windows, respectively, and having delineated on different radii thereof and in said annuli, indicia adapted to be selectively brought into registry in upright position with respective windows by rotation of the pins attached thereto, and a back board connected to said face plate bearing against said dials to retard rotation of the latter, indicia of said dials when brought into registry with said windows forming in combination complete indicia.

RUSSELL R. DEAN.
